(57) **CLAIM**

The ornamental design for a truck hood unit, as shown and described.

DESCRIPTION

FIG. 1 is a front perspective view of a truck hood assembly showing our new design;

FIG. 2 is a top plan view of the truck hood assembly of FIG. 1;

FIG. 3 is a bottom plan view of the truck hood assembly of FIG. 1;

FIG. 4 is a front elevational view of the truck hood assembly of FIG. 1;

FIG. 5 is a rear elevational view of the truck hood assembly of FIG. 1;

FIG. 6 is a left side elevational view of the truck hood assembly of FIG. 1; and,

FIG. 7 is a right side elevational view of the truck hood assembly of FIG. 1.

The broken lines in the drawings form no part of the claimed design.
